UNITED STATES PATENT OFFICE.

EDWARD S. STIMPSON, OF HOPEDALE, MASSACHUSETTS, ASSIGNOR TO
DUTCHER TEMPLE COMPANY, OF SAME PLACE.

LOOM-TEMPLE.

SPECIFICATION forming part of Letters Patent No. 288,742, dated November 20, 1883.

Application filed April 27, 1883. (No model.)

To all whom it may concern:

Be it known that I, EDWARD S. STIMPSON, of Hopedale, county of Worcester, State of Massachusetts, have invented an Improvement in Loom-Temples, of which the following description, in connection with the accompanying drawings, is a specification, like letters on the drawings representing like parts.

In this my invention the temple-head is connected with a temple-head-carrying plate provided with a vertical pin or foot, which is entered loosely within a socket made at the outer or free end of a horizontally-vibrating lever, having its fulcrum on a stud of a vertically-adjustable bracket attached to a stand secured to the inner side of and made adjustable on the breast-beam, to thus adapt the temple to cloth of different widths. The temple-head-carrying plate has suitable ears, to which is connected a tail-piece, which is extended backward through a guide-plate attached to the breast-beam.

Figure 1 represents in top view a portion of the breast-beam of a loom with one of my improved temples attached thereto, the full and dotted lines showing it in its two extreme positions, and in this figure the guide for the tail-piece is shown in section. Fig. 2 is a view of Fig. 1, looking at it in the direction of the arrow, Fig. 1, the lever being partially broken out to show the stand back of it; and Fig. 3 is a sectional detail on the dotted line $x-x$, Fig. 1, the pin or foot of the temple-head-carrying plate being in elevation.

The slotted stand B, having a long slot, 2, is connected to the inner side of the breast-beam A by bolt or nut 3, which permits the bracket to be adjusted on the breast-beam in accordance with the width of the fabric being woven. A part of this bracket B, at its end nearest the loom side, is projected upward to form a slotted guide, b, (shown in section, Fig. 1, and full lines, Fig. 2,) to serve as a guide for the tail-piece C, fastened to the ears 8 of the temple-head-carrying plate D by a pin, 4. The guide b, at one side, has a hook or projection, 5, to be engaged by the catch or shoulder 6 of the tail-piece C when the temple-head E is to be held back, as in dotted lines. The tail-piece C, near its outer end, has a block, c², adjustably attached to it by a screw, c³. The block

c², when it strikes the guide b, as in full lines, Fig. 1, limits the forward movement of the temple-head.

The inner end of the stand B is offset, as at 55 b², and is shown as provided with a rib, b³, to enter a correspondingly-shaped groove in the bracket F, which latter is slotted at f, and attached to the portion b² by a bolt or screw, f². The slot f permits the bracket F and its attached parts to be adjusted vertically to enable the temple-head to be correctly placed with relation to the height of the lay, and the rib b³ and groove prevent the bracket from being tipped over out of vertical position. The 65 bracket b² carries a stud or pin, b⁴, which serves as the fulcrum of the lever G, which lever is partially broken out in Fig. 2.

The outer end of lever G is bored or otherwise provided with a socket, (shown in section, 70 Fig. 3,) to receive loosely the pin or foot d, extended from the under side of the temple-head-carrying plate D, such connection enabling the latter to vibrate (more or less) horizontally about the pin d as a center as the lever G is 75 moved backward by the blow of the lay and forward by the spring H, (shown coiled about the stud b⁴,) one end of the said spring being held by bracket F, while its other end bears against the lug g of the lever G.

The temple-head E, having a toothed roller, e, is adjustably attached to the plate D by screws e². By pivoting the plate D, carrying the temple-head, as described, upon the lever G, and providing the inclined tail-piece C, 85 and extending the latter into and guiding it by the guide b, it is possible to maintain the temple-head and the axle of its roller e always in the same position or angle with relation to the reed, notwithstanding the varying positions of the temple under the action of the reed. The head E being carried by the arm or lever G, it is obvious that the roller e, in engagement with the fabric, will act to stretch the fabric as the filling is being beat up, and 90 the arm or lever G turns on its pivot toward the breast-beam. The temple-head having been set on the carrier-plate D, with the roller e parallel with the reed, or at an angle thereto, (as is at times desired by some manufacturers,) 100 and the carrying-plate being pivoted, the tail-piece C in the guide b will insure that the said

head and roller shall always maintain the same relative position with relation to the reed under all positions of the lever G as it is moved backward and forward by the lay. The temple-head-carrying plate and temple-head might be in one piece.

I claim—

1. The lever G, means to support it, the oscillating temple-head, and a tail-piece or projection, combined with a guide for the tail-piece, whereby the temple-head is permitted to oscillate on the said lever as the latter is moved toward and from the breast-beam, substantially as described.

2. The temple-head, its loosely-pivoted carrying-plate, the lever to support it, the tail-piece, the stand, and the guide for the tail-piece, combined with the bracket adapted to be adjusted vertically, and the spring to act upon the said lever, substantially as described. 15
20

In testimony whereof I have signed my name to this specification in the presence of two subscribing witnesses.

EDWARD S. STIMPSON.
